UNITED STATES PATENT OFFICE.

WILLIAM ADAMS SMITH, OF KINGSTON, ONTARIO, CANADA.

HANGER-RACK.

1,264,342.

Specification of Letters Patent. Patented Apr. 30, 1918.

Application filed June 4, 1917. Serial No. 172,707.

To all whom it may concern:

Be it known that I, WILLIAM A. SMITH, a subject of the King of England, residing at Kingston, in the Province of Ontario and 5 Dominion of Canada, have invented certain new and useful Improvements in Hanger-Racks, of which the following is a specification, reference being had to the accompanying drawings.

10 This invention relates to an improved hanger rack, and has for its primary object to provide a folding rack which can be easily and quickly applied to a tent pole or removed therefrom, and may be conveniently 15 employed for supporting articles of clothing or other equipment.

It is another and more particular object of the invention to provide a device of this character, consisting of a plurality of foldable hanger bars, and means for retaining 20 said bars in operative relation to each other in their applied position on the tent pole.

It is also an additional object of the invention to provide a device for the above 25 purpose, which is simple and inexpensive in its construction, as well as strong and durable, and may be very compactly folded so that it will occupy but little space in shipment.

30 With the above and other objects in view, my invention consists in the novel features of construction, combination and arrangement of parts to be hereinafter more fully described, claimed, and illustrated in the 35 accompanying drawing, in which,

Figure 1 is a plan view showing one embodiment of my improved hanger rack applied to a tent pole;

Fig. 2 is a section taken on the line 2—2 40 of Fig. 1;

Fig. 3 is a perspective view of the rack folded;

Fig. 4 is a plan view showing a slightly modified construction of the rack; and

45 Fig. 5 is a similar view illustrating a further modification of the device.

Referring in detail to the drawing and more particularly to Figs. 1, 2 and 3 thereof, 5 designates a plurality of hanger bars 50 which may be of either wood or metal, said bars being arranged in pairs and in spaced relation to each other. The spaced bars in one pair are permanently pivoted to one of the bars in the other pair by means of the 55 bolts 6, said pivot bolts being located in spaced relation to the ends of the bars. One

of the bars in said first named pair is also permanently pivoted to the other bar of the second pair by means of the bolts 6'. The other of the first named bars is adapted to 60 be removably connected to the other bar in the latter pair by means of the bolt 7, upon which a nut 8 may be detachably threaded or, if desired, this bolt may be provided with a transverse opening to receive the hasp of 65 a padlock. It will thus be seen from this construction that the bars 5 in each pair may be disposed in parallel relation to each other and in intersecting relation to the bars in the other pair, said bars being disposed upon 70 relatively opposite sides of a tent pole, indicated at T, in tangential relation thereto.

The members 9 which may be either of wood or metal, are driven upwardly between the inner sides of the bars 5 in one pair and 75 the opposed sides of the tent pole, so as to exert a wedging clamping action upon the pole and the hanger bars and thus retain the latter in their proper adjusted positions upon the pole. The ends of the several hanger 80 bars projecting beyond the pivots 6, 6' and the bolt 7, afford means to receive garments or other articles. If desired, the wedge members 9 may be connected to the bars 5 in one pair by means of short chains indicated at 10, so that the possibility of loss of 85 these wedge members will be obviated.

In Fig. 4 of the drawing, I have illustrated a modified construction of the device, wherein three of the bars 5' are provided, 90 two of which are permanently connected to each other by a suitable pivot and one of said bars being permanently connected to the remaining bar in spaced relation to its end by a similar pivot. 7' designates the 95 removable bolt which connects the latter bar to the other of the first named bars. In the application of this device to the tent pole, the bars are moved relative to each other and arranged in the form of a triangle with 100 their inner edges engaged with the periphery of the pole. In this construction, I have indicated a collar C on the tent pole, upon which the inner edges of the several bars 5' rest and by which said hanger bars are supported. This collar or sleeve may be the connecting member between sections of the poles. It is manifest, however, that if desired, the removable wedges above referred to can be used in connection with this form 105 of the invention.

In Fig. 5, I have shown another modified

construction wherein only two bars 5^a are provided, which are adapted to be arranged upon relatively opposite sides of the pole and are provided with angular lugs 11. The 5 lug on each bar projects toward the other of the bars, said latter bar having an opening formed therein to receive a screw 12 adapted to be threaded into the lug, whereby the bars may be drawn into tight clamping engagement 10 against the pole.

In the form of the device as above described, it will be appreciated that the hanger rack can be very easily and quickly applied to the tent pole or removed therefrom, and when removed, the several parts 15 of the hanger may be compactly folded so that they will occupy but little space in packing for shipment. It will thus be seen that I have provided a hanger which is admirably adapted for army use, as it may be 20 very easily and quickly applied or removed from the tent pole. The device is also strong and durable and affords a very serviceable supporting means for clothes or camp equipment. The rack can, of course, be made in 25 various sizes and any desired number of the racks can be applied to the pole.

While I have herein shown and described the preferred construction and arrangement 30 of the several elements of the device, it is to be understood that the same are susceptible of considerable modification and I, therefore, reserve the privilege of adopting all such legitimate changes as may be fairly 35 embodied within the spirit and scope of the invention as claimed.

If desired, suitable hanger hooks or nails may be secured to each of the bars 5 as additional suspending means for garments or 40 other articles.

Having thus fully described my invention, what I desire to claim and secure by Letters Patent is:

1. A hanger rack consisting of a plurality 45 of pivotally connected bars adapted to be arranged in intersecting relation with their ends projecting divergently beyond the

points of intersection, removable means to be engaged with certain of the bars at their point of intersection whereby the bars are 50 held against relative pivotal movement, and means for sustaining said bars in contiguous tangential relation to a support.

2. A hanger rack consisting of a plurality of bars connected for folding movement 55 upon each other, said bars being adapted for arrangement in intersecting relation, means for removable engagement with certain of said bars to hold the same in intersecting relation against relative movement, and 60 means to coact with certain of the bars to retain the several bars in contiguous tangential relation to a support.

3. A hanger rack consisting of a plurality of bars pivotally connected for folding 65 movement upon each other, said bars being adapted to be arranged in intersecting relation and tangentially positioned with respect to a supporting pole, means for holding the bars in such position against relative pivotal movement, and means attached to certain of the bars and adapted to be inserted between said bars and the pole to detachably secure the hanger rack in its adjusted position upon the pole. 70

4. A hanger rack consisting of a plurality of bars pivotally connected to each other for relative movement, said bars being adapted to be arranged in intersecting pairs, the bars in each pair being disposed in spaced relation and adapted to be disposed upon opposite sides of a tent pole, means for holding said bars against relative pivotal movement, and removable means insertible between certain of the bars and the opposite sides of the 85 pole to detachably clamp the hanger rack in place against bodily shifting movement with respect to the tent pole.

In testimony whereof I hereunto affix my signature in the presence of two witnesses. 90

WILLIAM ADAMS SMITH.
